UNITED STATES PATENT OFFICE.

WILLIAM C. COLEMAN, OF WICHITA, KANSAS.

CENTRIFUGAL MACHINE.

Application filed August 6, 1923. Serial No. 656,101.

This invention relates to centrifugal separators and amalgamators and the primary object is to provide a simple, efficient device which subjects the metal-laden ore, generally in the form of sludge, to amalgamator action, and then to a concentrator action.

In illustrating my invention I have shown the amalgamator as the upper element with an upper intake, the amalgamator containing mercury to receive the metal from the ore. The lower portion of the amalgamator is shown as discharging into a concentrator which separates the heavier particles of ore which have not been absorbed by the mercury in the amalgamator.

Mercury will amalgamate free gold only, but gold and sulphid ore is not taken up by mercury. Therefore, after the ore has passed through the amalgamator to allow the separation of the free gold it is subjected to the centrifugal action of the concentrator which separates out the heavier particles, which are then discharged from the periphery of the concentrator, the sludge passing out through the center of the concentrator.

The amalgamator chamber and the concentrator chamber can be secured together so that they will rotate at the same speed and whereby a compact machine can be provided, permitting the ore to pass through in a steady stream from the amalgamator chamber to the concentrator chamber and discharge therefrom. In each chamber the metals will be separated, for example, free gold in the amalgamator and sulphid gold or heavy particles of gold in the concentrator.

The peculiarly novel construction of the illustrated embodiment of my invention will be apparent by reference to the following description in connection with the accompanying drawings, in which

Fig. 1 is a vertical, longitudinal, sectional view through amalgamator and concentrator chambers constructed in accordance with my invention, and

Fig. 2 is a perspective view of the concentrator casing, parts being broken away to show the interior thereof.

The separator is shown as consisting of two casings 1 and 2; the first, the amalgamator casing and the second the concentrator casing. They have outstanding flanges 3 and 4 by means of which they may be fastened together through the medium of fastening devices illustrated as bolts 5. Obvi-

ously, additional casing members may be added. Ordinarily, two will be sufficient but if desired, the units may be multiplied.

The member 1 is provided with a cap or cover member 6 having an inlet 7 and fastened to the member 1 by the bolts 5, which pass through the flange 8 and through the flanges 3 and 4 (see Fig. 1). Each of the members 1 and 2 has a conical bottom member 9 with a central outlet opening 10 surrounded by a collar 11 carrying bolt sockets 12 extending above the collar 11. Resting upon the bolt sockets or supports 12 in each case is a distributor disk 13, having a depending flange 14, intermediate the ends of which is a distributor flange or collar 15.

The members 1 and 2 have offset portions or shoulders 16 to receive a packing ring 17 and resting upon the packing ring is a gasket 18 to pack the joints between the members 1 and 2 or the member 1 and the cover 6.

The distributor is spaced from the wall of its casing and also from the collar; that is, it is interposed between the collar and the wall of the casing so that a tortuous passageway is provided for the sludge. The sludge first enters through the inlet 7 of the amalgamator and is deposited on the distributor where, due to centrifugal force, it is thrown off against a body of mercury 19 in the mercury space 20; that is, the mercury ring 19 will lie against the inner face of the casing or rotor wall so that as the sludge or pulp follows the path indicated by the arrows, it will first be subjected to the action of the mercury and then to the action of the concentrator and finally be discharged through the opening 10.

If two casings are used, as shown in Fig. 1, the discharged material which passes through the opening in the upper casing will be deposited on a next succeeding distributor and follow the same path that it had traversed in the first casing, the action being that the sludge or pulp will pass over the body of mercury to permit the mercury to take up the metal; after the sludge has passed out of the machine, the metal can be recovered from the mercury. The metal which is separated from the sludge in the concentrator 2 will flow out through pipe 21 in a continuous stream.

The distributor is shown as rigid with the casing; therefore, it rotates at the same speed but as the material is thrown off by

centrifugal force against the body of mercury, the mercury band will have a tendency to rotate relative to the sludge so that the sludge will have a rolling contact on the body of mercury and as the sludge works over the body of mercury, the metal will be taken out in an obvious manner.

It will be seen from the foregoing that I have provided a separator comprising an amalgamator and a concentrator so that the free gold can be recovered from the ore by amalgamation with the mercury and the sulphid metals or larger particles of metal can be separated by centrifugal action in the concentrator. Therefore, a greater recovery will result than if either one of the chambers were used alone.

What I claim and desire to secure by Letters-Patent is:

1. A centrifugal separator comprising a casing having an inlet and an outlet, upstanding supporting members carried by the

casing, a disk fast on the casing, a flange depending from the disk, and a distributing collar between the ends of the flange. 25

2. A centrifugal separator comprising a casing having an inlet and an outlet, the bottom having the outlet, a collar surrounding the outlet, upstanding socket members about the collar, a disk on the socket members, bolts passing through the disk and engaging the socket members, and distributing means on the ends of the disk. 30

3. A centrifugal separator comprising a casing having an inlet and an outlet, the casing having a mercury chamber, a distributor within the casing for distributing material into the mercury chamber, and means for securing a complementary casing of like construction to the first named casing. 35

In testimony whereof I affix my signature.

WILLIAM C. COLEMAN.
